PORTABLE TELEPHONE DIAL SPRING TENSION TESTER AND ADJUSTER OR SIMILAR ARTICLE

Glenn E. Clarridge, Santa Cruz, Calif., assignor to Sylvania Electric Products Inc., a corporation of Delaware

Filed Dec. 29, 1965, Ser. No. 366

Term of patent 14 years

(Cl. D26—14)

FIG-1

FIG-2

FIG-3

FIG-4

FIGURE 1 is a perspective view of a portable telephone dial spring tension tester and adjuster or similar article showing my new design;

FIGURE 2 is a front elevation thereof;

FIGURE 3 is a side elevation thereof; and

FIGURE 4 is a rear elevation thereof.

I claim:

The ornamental design for a portable telephone dial spring tension tester and adjuster or similar article, as shown.
